UNITED STATES PATENT OFFICE

2,460,299

LIP ROUGE DISPENSER APPLICATOR

Ralph E. Kruck, Longmeadow, Mass.

Application April 27, 1946, Serial No. 665,435

7 Claims. (Cl. 132—88.7)

1

This invention relates to improvements in dispenser applicators for lip rouge and the like.

The principal objects of the invention are directed to the provision of novel dispensing applicator device for applying lip rouge which is characterized by its simplicity in construction and efficiency in operation and is accomplished by the novel combination and arrangement of parts hereinafter to be more fully described.

With the foregoing and various other novel features and advantages and other objects of my invention as will become more apparent as the description proceeds, the invention consists in certain novel features of construction and in the combination and arrangement of parts as will be hereinafter more particularly pointed out in the claims hereunto annexed and more fully described and referred to in connection with the accompanying drawings wherein:

Fig. 1 is a longitudinal view partly in section and partly in elevation of a lip rouge dispenser applicator embodying the novel features of the invention;

Fig. 2 is a sectional view on the line 2—2 of Fig. 1;

Fig. 3 is a sectional view of the line 3—3 of Fig. 1.

Fig. 4 is a side elevational view of the applicator tip.

Referring now to the drawings more in detail, the invention will be fully described.

A barrel 2 is provided which is in the form of a tube and has a lower end portion 4 which is preferably reduced in diameter. The barrel provides a chamber or container for rouge and the upper end thereof is internally threaded to receive a threaded lower end of a ferrule member 6, as shown.

The ferrule 6 is preferably tubular in form and it has an applicator 8 secured therein in some suitable manner. A removable cap 10 fits over the upper end of the ferrule 6 so as to enclose the applicator 8. The applicator 8 is preferably made from yieldable material such as rubber or a rubber composition. Said applicator in the preferred form of the invention has an outer non-porous peripheral portion 12 and an inner relatively more porous portion 14 which is provided with an axial bore 16. The inner portion may be of sponge rubber.

The applicator 8 is slightly yieldable and its outer end is concaved at 18, as shown, to provide opposite peripheral points 20. Lip rouge is carried in the bore 22 of the barrel and it may be inserted therein in the form of a stick through the upper end of the barrel when the ferrule 6 is removed by unscrewing therefrom.

2

The rouge is forced upwardly in the barrel and through the passageway 16 in the applicator 8 by means to be described. The construction will be such that the desired small amount of rouge will be emitted from the passageway 16 to the concaved end of the applicator.

The curvature of the end of the applicator preferably will be such as to provide one or more points such as 20. With the barrel held in the hand the rouge on the end of the applicator may be readily applied to the lips. The points 20 provide means for defining the area or shape of the rouge on the lip as the applicator is drawn thereacross.

15 The lower portion 4 of the barrel 2 is internally screw-threaded and a propeller 24 which is externally threaded is in screw-threaded engagement therewith. The said propeller 24 is preferably tubular in form and a member 26 is secured in any convenient manner to the upper end thereof. Said member may take any form and a piston 28 which may be in the form of a yieldable cup washer has a washer 30 therein. A screw or rivet 32 secures the members 26, 28 and 30 together whereby the piston is secured to the upper end of the propeller.

20 A tubular operating member or sleeve 34 is arranged for telescopic movement relative to the barrel and it has a lower wall 36 which is provided with an opening around the propeller 24, as shown. A lip or lips such as 38 are disposed in a notch or notches 40 at the lower end of the propeller see Fig. 3. A lower closure 42 is internally threaded and is in screw-threaded engagement with the lower end of the propeller, to secure the operating member and propeller in engagement and to close the open end of the propeller, as shown.

25 With lip rouge within the chamber 22 of the barrel, the operating member may be rotated in one direction so as to turn the propeller and thereby move the piston upwardly so that it acts on the rouge in the chamber and forces it upwardly to and through the applicator.

30 The screw threads on the propeller member 24 are preferably of relatively fine pitch, say forty threads per inch or so. This makes it necessary to rotate the operating member through a considerable angle in order to obtain endwise motion of the piston whereby a small amount only of the rouge is forced upwardly.

35 The propeller, as stated, is preferably tubular in form and by removing the lower closure 42 a vial of perfume or the like may be inserted therein, or it may be used for enclosing other objects.

40 The operating member 34 is, of course, rotated in one direction to dispense the rouge. When

the chamber is empty the operating member may be rotated in an opposite direction to retract the piston so that with the ferrule 6 removed rouge may be inserted in the barrel in the form of a stick or otherwise.

It will be observed that the device is constructed from relatively few components so as to be simple in form and economical of manufacture while at the same time efficient in operation.

The invention may be embodied in other specific forms without departing from the essential characteristics thereof. Hence, the present embodiments are therefore to be considered in all respects merely as being illustrative and not as being restrictive, the scope of the invention being indicated by the appended claims rather than by the foregoing description, and all modifications and variations as fall within the meaning and purview and range of equivalency of the appended claims are therefore intended to be embraced therein.

What it is desired to claim and secure by Letters Patent of the United States is:

1. A device for dispensing and applying lip rouge comprising in combination, a container for lip rouge, an applicator at one end of the container having a longitudinal dispensing passageway therethrough, and means for forcing rouge in the container into and through the passageway of the applicator, said applicator including an elongated body made from relatively porous yieldable material having relatively non-porous peripheral longitudinal outer side portions and a porous outer end.

2. A device for dispensing and applying lip rouge comprising in combination, a container for lip rouge, an applicator at one end of the container having a longitudinal dispensing passageway therethrough, and means for forcing rouge in the container into and through the passageway of the applicator, said applicator including an elongated body made from relatively porous yieldable material having relatively non-porous peripheral longitudinal outer side portions and a porous outer end, and said outer end being concaved transversely to the longitudinal axis thereof of providing lips at the outer end of the applicator and at opposite sides thereof disposed above the plane of said end therebetween.

3. A device for dispensing and applying lip rouge comprising in combination, an elongated tubular barrel adapted to serve as a container for lip rouge and having relatively thin side walls, the lower end portion of said barrel being reduced in diameter relative to the diameter of the main body of the barrel thereabove and said lower portion provided with internal screw threads and the interior of the wall of barrel above said bore being smooth, inner and outer concentrically related and radially spaced elongated tubular propeller and operating members having relatively thin side walls, lower connections between the lower ends of said propeller and operating members, said propeller member being externally screw threaded and in engagement with the internal screw threads of said barrel, and a piston reciprocable in said barrel adapted to be operated by said propeller, said barrel, propeller and operating member arranged whereby the propeller may be rotated by said operating member so that said propeller and piston are moved upwardly in the barrel while the barrel above the lower portion thereof is moved downwardly between and out of contact with the propeller and operating members, and a one-piece

applicator tip closing the upper end of the barrel member having an opening therethrough and provided with an outer end face which is concaved transversely, said connections including a lower transverse wall on the lower end of the operating member having an opening through which the lower end of the propeller member extends and the lower end of the propeller member provided with an axial slot in the side wall thereof in which is disposed a lip extending inwardly from the periphery of the opening in the transverse lower wall of the operating member.

10 4. A device for dispensing and applying lip rouge comprising in combination, a container for lip rouge, an applicator at one end of said container having a longitudinal dispensing passageway therethrough and means for forcing rouge in said container into and through the passageway of said applicator, said applicator including an elongated body made from a relatively porous yieldable material.

15 5. A device for dispensing and applying lip rouge comprising in combination, a container for lip rouge, an applicator at one end of said container having a longitudinal dispensing passageway therethrough and means for forcing rouge in said container into and through the passageway of said applicator, said applicator including an elongated body made from a relatively porous yieldable material, and having means for defining the area of the rouge on the lip as said applicator is drawn thereacross.

20 6. A device for dispensing and applying lip rouge comprising in combination, a container for lip rouge, an applicator at one end of said container having a longitudinal dispensing passageway therethrough and means for forcing rouge in said container into and through the passageway of said applicator, said applicator including an elongated body made from a relatively porous yieldable material, and having a peripheral rouge outlining point for defining the area of the rouge on the lip as said applicator is drawn thereacross.

25 7. A device for dispensing and applying lip rouge comprising in combination, a container for lip rouge, an applicator at one end of said container having a longitudinal dispensing passageway therethrough, and means for forcing rouge in said container into and through the passageway of said applicator, said applicator including an elongated body having a relatively non-porous peripheral outer side portion for defining the area of rouge on the lip as said applicator is drawn thereacross.
